ROY D. KING, OF CHICAGO, ILLINOIS, ASSIGNOR TO COIN CONTROLLED LOCK COMPANY,
OF CHICAGO, ILLINOIS, A CORPORATION OF CALIFORNIA.

COIN-CONTROLLED LOCK

1,283,802.

Specification of Letters Patent.

Patented Nov. 5, 1918.

Application filed June 2, 1916. Serial No. 101,212.

To all whom it may concern:

Be it known that I, ROY D. KING, a citizen of the United States, residing at Chicago, in the county of Cook and State of Illinois, have invented certain new and useful Improvements in Coin-Controlled Locks, of which the following is a specification.

This invention relates in general to locks, and has more particular reference to coin-controlled locks, for use on parcel lockers and in similar places where it is necessary to deposit a coin in the lock before the lock can be operated. In this type of lock the user after depositing his coin and locking the lock withdraws the key and carries it with him as his check until such time as he desires to reopen the locker or container. The lock is then unlocked by means of the key which, upon unlocking movement of the lock, becomes automatically engaged therein so that it cannot be again withdrawn until another coin has been deposited and the lock locked.

One of the primary objects of my present invention is to provide a coin-controlled lock of this general character which will be simple in construction and positive and certain in its operation.

Another object is to provide a lock which can only be operated by a coin of a predetermined size, but which will permit the passage therethrough of coins or slugs of smaller size, and when the lock is locked will prevent the deposit of another coin therein.

Still another object of my invention is to provide improved means for positively operating upon a coin deposited in the lock so that the mechanisms which normally prevent locking movement of the lock will be positively actuated by the coin, after which the coin will be positively ejected from the lock.

Other objects and many of the attendant advantages of my invention will be readily appreciated as the same is better understood by reference to the following description when considered in connection with the accompanying drawings.

Referring to the drawings,—

Figure 1 is a rear elevation of a lock embodying my invention;

Fig. 2 is a sectional view taken on the line 2—2 of Fig. 1;

Fig. 3 is a rear elevation of the lock, cer-

tain of the parts being removed or broken away to more clearly show the parts behind;

Fig. 4 is a fragmentary view showing some of the parts shown in Fig. 3 in the position which they assume upon insertion 60 of a key in the lock;

Fig. 5 is a fragmentary sectional view showing the indicator disks and the operating mechanisms therethrough;

Fig. 6 is a longitudinal sectional view 65 through the center of the key-cylinder;

Fig. 7 is a transverse sectional view on the line 7—7 of Fig. 6;

Fig. 8 is a detail perspective view of the cylinder with the tumblers removed; and 70

Fig. 9 is a perspective view of one of the tumblers.

On the drawings reference character 11 indicates generally the front or case of the lock, preferably formed of heavy sheet 75 metal and upon which the operating mechanisms are carried. A housing or frame 12, secured to the rear face of the casing by bolts 13 or otherwise, forms a bearing support for the key-cylinder 14, the detail construction of which, and the tumblers mounted therein, will be later described, the cylinder being adapted to be oscillated in the housing by means of a key 15. A locking bolt 16, guided at one end in an aperture 17 80 formed in a rearwardly projecting flange 18 of the casing, is pivotally connected by a pin 19 to an arm 21 rigidly attached to the key-cylinder intermediate its ends, and by which said bolt is projected or retracted 90 upon oscillatory movements of the cylinder.

Beneath the cylinder the front of the casing is provided with a coin-receiving aperture 22 through which a coin is deposited in the lock in a coin-chute 23 formed by a piece 95 of metal secured to the rear face of the casing. At the lower end the member forming the back of the chute is cut away as indicated at 24 on each side, and upon the rear face of this member there is pivoted at 26 a 100 pair of members 27 and 28, respectively, having their lower ends inturned as indicated at 29 and projecting across the edges of the chutes in the cut-away portions thereof, as shown in Figs. 1 and 2. The member 105 27 is provided with a laterally projecting arm 31 and the member 28 is provided with a similar arm 32, the two arms being yieldingly connected together by a tension spring 33 which yieldingly urges the inturned ends 110

of said arms into the position shown in Fig. 1. The ends of the members are spaced apart a distance slightly less than the diameter of the coin 34 for which the lock is 5 designed, so that when a coin of this size is deposited in the coin-chute through the opening 22 it will be sustained by these in-turned ends 29 in the position shown in Fig. 1, while smaller coins will drop through.

10 An ejector 35 slidably mounted in the coin-chute has an upwardly extending portion 36 which is pivotally connected at 37 with an arm 38 rigidly attached to the key-cylinder 14, so that as the cylinder is oscillated the ejector is moved up and down in 15 the coin-chute. The lower end of the ejector is bifurcated and shaped to present diverging coin-engaging surfaces 39 as shown in Fig. 3. The rear wall 23 of the coin-chute 20 is formed to provide a central boss or projection 41 which the bifurcated ends of the ejector straddle when the ejector is in its uppermost position, as shown in Fig. 2. The ejector is also provided with a boss or 25 projection 42 which, by engagement with the rear face of the lock casing above the aperture 22, normally holds the ejector away from the opening, as shown in Fig. 2, to permit the insertion of a coin therein. After a 30 coin has been deposited in the chute where it is sustained by the in-turned ends 29 of the members 27 and 28 initial downward movement of the ejector, effected by turning the key-cylinder, will cause the ejector to 35 move toward the casing wall over and into alinement with the coin. It will be obvious that this movement will be caused by the projection 41 which moves the ejector from the position shown in Fig. 2 to a position 40 against the rear face of the casing 11 and into alinement with the deposited coin 34. Continued downward movement of the ejector will force the coin out between the members 27 and 28, the lower ends of which separate 45 under the thrust of the coin against the force of the spring 33. This separation of the lower ends of the members 27 and 28 brings their upper ends, which normally extend laterally in opposite directions from 50 a median line, substantially into alinement as shown in Fig. 3, thereby permitting the downward movement of the ejector and the operation of the lock which, when the members 27 and 28 are in normal position, is prevented 55 by mechanism which will now be described. It should be observed at this point that when the ejector is in lowered position it lies close against the rear face of the casing 11 thereby covering the opening 22 and 60 preventing the insertion of another coin so long as the lock remains in locked position. Upon the rear face of the ejector 35, above the coin-chute, there is mounted a rearwardly projecting abutment member 43 provided with an opening 44 disposed in axial

alignment with a median line drawn longitudinally through the pivoted members 27 and 28. When these members are in their normal position, as shown in Fig. 1, their upper ends are separated sufficiently to prevent their entrance into the opening 44 when the ejector is depressed. Normally, therefore, if an attempt is made to lock the lock by turning the key without depositing a coin in the slot the ejector will move downwardly until this abutment 43 engages the upper ends of the members 27 and 28 which will prevent further locking movement of the lock. If a coin is deposited in the coin slot, however, initial downward movement 75 of the ejector will force the coin between the in-turned ends 29 of the members 27 and 28 as previously described, thereby rocking the members on their pivot to overlap their upper ends so that these overlapped ends 80 will pass through the opening 44 upon downward movement of the ejector, thereby permitting a full operative locking stroke of the lock. The position of the parts with the upper ends of the members 27 and 28 projecting through the abutment 43 when the lock is in locked position is shown in Fig. 3. After withdrawal of the key the lock is of course maintained in locked position by the tumblers in the key-cylinder 14 in a manner 85 which will be later described.

For the purpose of normally but yieldingly maintaining the parts in unlocked position I have provided a tractile spring 45 secured at its upper end to a pin 46 fixed in 100 the housing 12 and attached at its lower end to a finger 47 pivoted at 48 to the lower end of the housing 12 and extending beneath a projection 49 on the abutment member 43. The spring 45, operating through the finger 105 47, normally tends to elevate the ejector, thereby urging the lock mechanism into unlocked position.

It sometimes happens in locks of this general character that the user after locking the 110 lock will, before removing the key accidentally unlock it again. Since the coin which was utilized to effect the locking of the lock has been ejected at the completion of the locking movement it is obvious that the use 115 of this coin has been lost and the customer must deposit another coin in order to lock the lock again. With a view to obviating this difficulty I have provided in the present instance a "fool proof device" which prevents unlocking of the lock until the key has 120 been withdrawn and reinserted therein. This device comprises, generally speaking, a pawl adapted, under certain conditions, to engage with an abutment carried by the key-cylinder and prevent unlocking movement of the 125 cylinder.

This pawl, which is designated generally by reference character 51, comprises a body portion provided with an elongated slot 52, 130

a tail portion 53, and a finger or beveled end 54 adapted to engage with an abutment or shoulder 55 carried by an arm 56 rigidly attached to the key-cylinder. The pawl is 5 mounted upon a pin 57 which extends through the slot 52 so that the pawl is pivotally supported upon said pin and is also 10 slideable relatively thereto. When the lock is in unlocked position the pawl is normally held in position shown in Fig. 1 by a small 15 spring 58 coiled upon the pin 46 and having an end projecting laterally therefrom through an opening 59 in the pawl, this spring being adapted to normally depress the rear end of 20 this pawl so that the pawl assumes the position shown in Fig. 1, as previously stated. The tail 53 of the pawl projects downwardly through a slot in the key-cylinder into the path of the key 15 when positioned in the 25 cylinder. Assuming that the lock is in unlocked position with the parts disposed as shown in Fig. 1; when the lock is locked by turning the key in a counter-clockwise direction, viewing this figure, and after the deposit of a coin, as previously explained; the shank of the key engages the tail 53 and moves the pawl on its pivot into the position shown in full lines in Fig. 3, in which position the end 54 is disposed beneath the abutment 55 so that reverse rotation of the key-cylinder is prevented. The lock cannot be 30 unlocked until the key has been withdrawn and reinserted to release the pawl. When the key is withdrawn the pawl will be rocked 35 on its pivot by the spring 58 into the position shown in dotted lines in Fig. 3, the end 54 of the pawl being still in the path of the abutment 55 so that it acts, in addition to the tumblers, as a preventive against unlocking 40 of the lock. The arm 56 is also provided with an auxiliary abutment 61 which will engage with the end 54 of the pawl and prevent unlocking movement in case the lock has not been completely locked so as to bring 45 the abutment 55 above the end of the pawl. This construction insures a complete stroke upon the locking movement before the unlocking movement can take place. It will be observed from the position of the pawl 51, 50 shown in dotted lines in Fig. 3, that when the key has been withdrawn the tail 53 lies directly across the key-way opening so that it will be engaged by the key when it is inserted. The reinsertion of the key therefore 55 lifts the pawl from the position shown in dotted lines in Fig. 3 to the position shown in Fig. 4, thereby withdrawing the end 54 from the path of travel of the abutments 55 and 61 so that the lock can be turned to 60 unlocked position whereupon the pawl will resume its original position, as shown in Fig. 1.

In order that the attendant in charge of the lockers or other receptacles upon which 65 these locks are employed may be able to as-

certain how many times the lock has been used and therefore how many coins should be in the till, I have provided an indicator or recording device which records each operation of the lock. This device comprises a 70 pair of concentrically mounted toothed disks 62 and 63, the outer surfaces of which are provided with indicia in the form of letters or figures corresponding in number to the 75 number of teeth on the periphery of the disks. A sight opening 64 is provided in the front wall of the casing through which the characters may be read. Upon the cylinder just back of the disks I have mounted an arm 80 65 which carries a spring-pawl 66 of sufficient width to engage with the teeth of both disks. The pawl is reciprocated at each oscillation of the key-cylinder a distance sufficient to move the disks forward one tooth. It will be observed from Fig. 5 that the disk 85 62 is provided with one deep tooth 67 which will permit the pawl 66 to also engage with a tooth of the disk 63 so that when this tooth 67 is engaged by a pawl both the disks will be simultaneously moved one step. The remaining teeth on the disk 62 are shallower so as to prevent the engagement of the pawl 66 with the disk 63. The disk 62 will therefore be moved by the pawl 66 one step at a time until it has completed a revolution, 90 while the disk 63 will remain stationary. After a complete revolution the tooth 67 is again engaged by the pawl 66 whereupon disk 63 will also be moved forward one step. Suitable spring-pawls 68 and 69 engage with 95 the teeth of both disks to hold the disks against retrograde movement and accidental forward movement.

The mechanism thus far described may be used in connection with a cylinder and key 100 of any approved construction, such, for instance, as the pin tumbler cylinders commonly employed in what is commercially known as a Yale lock. In Figs. 6 to 9 inclusive I have illustrated, however, in detail 105 a novel and improved key and cylinder tumblers which I prefer to use in this type of lock.

The cylinder 14 in this instance is provided with an elongated slot 71 extending 110 transversely therethrough in which are slidably arranged a series of disk tumblers 72. The housing 12 is provided above and beneath the bore in which the cylinder 14 is mounted with grooves 73 and 74 adapted to 115 receive the ends of the tumblers 72 whereby the cylinder is held against rotation. Each tumbler is provided with a key-receiving aperture 75, the apertures being disposed at different positions longitudinally of the 120 tumblers when their ends are in alinement, as shown in Fig. 6. The key 15 is serrated on both edges, and it will be observed that the corresponding faces on opposite edges are parallel; that is, any point on one edge of 125 130

the key is equi-distant from a corresponding point on the opposite edge, and the distance between corresponding points on opposite edges of the key is substantially equal 5 to the length of each of the apertures 75 in the tumblers. The result is that each of the tumblers is positively moved in both directions by the key upon its withdrawal and insertion and no dependence is placed for the 10 operation of the tumblers upon either gravity or springs. In order to facilitate withdrawal and insertion of the key the top and bottom edges of the apertures 75 in the tumblers are beveled or reduced in thickness, as 15 indicated by reference character 76. This insures easy movement of the key. Furthermore, in order to prevent binding of the tumblers against each other and to insure that they will always be in the proper position 20 when the key is inserted to operative position in the lock, the key is constructed to provide flat tumbler-supporting surfaces disposed at right angles to the axes of the tumblers upon which the tumblers rest when 25 the key is turned. This will be evident from an inspection of Fig. 6, from which it will be seen that every tumbler rests upon a flat surface extending parallel with the longitudinal axis of the key, and these surfaces, while 30 short, are of sufficient length to permit a slight variation in the longitudinal position of the key without disarranging the tumblers. When the key is fully inserted to operative position, as shown in Fig. 6, the 35 ends of all the tumblers are withdrawn from the locking grooves 73 and 74 and alined within the perimeter of the cylinder so that the cylinder may be turned within the housing. When the lock is in unlocked position 40 the tumblers will prevent withdrawal of the key, as they are held against longitudinal displacement by the surrounding walls of the housing. When, however, the lock is in locked position the key may readily be withdrawn, 45 since the tumblers will be forced either up or down into the grooves 74 or 73, as the case may be, as the key is withdrawn, and the engagement of the ends of the tumblers in these grooves will prevent turning 50 movement of the cylinder until they have all been realined by reinsertion of the proper key. In order to insure a positive movement of all of the tumblers upon withdrawal of the key it is provided near its inner end with 55 a tooth 77 which is longer than any of the other serrations so as to engage with the tumblers in succession and positively move each of them out of alinement with the periphery of the cylinder. It should be understood 60 that the cylinder, tumblers and key above described are capable of use in locks of various types other than coin-controlled locks, and the structural features thereof are claimed in an application filed concurrently 65 herewith.

It is believed that my invention, its mode of operation and many of its advantages will be understood from the foregoing without further description, but it should be obvious that the details of construction illustrated 70 and described may be varied within considerable limits without departing from the spirit of the invention as set forth in the following claims.

I claim:—

1. In a lock, the combination of a bolt, key-actuated means for operating said bolt, coin-controlled mechanism including a member pivotally mounted on a stationary pivot for preventing locking of the lock except 80 upon the deposit of a coin therein, and means for rocking said member on its pivot into inoperative position through the instrumentality of a coin upon initial locking movement of said bolt. 85

2. In a lock, the combination of a bolt, key-actuated means for operating said bolt, coin-controlled mechanism including a pair of concentrically pivoted members adapted to normally prevent locking of the lock, and means movable simultaneously with said bolt for initially moving said member to inoperative position through the intermediary of a coin, and subsequently ejecting said coin 90 from operative relation with said members. 95

3. In a lock, the combination of a bolt, key-actuated mechanism for operating said bolt, a coin chute, movable mechanism unconnected with said key-actuating mechanism and normally extending into said chute, 100 means movable with said bolt, arranged to be arrested in its movement by said mechanism to prevent locking of the lock when there is no coin in the chute, and means also movable with said bolt for operating upon a coin in said chute so as to move said mechanism to inoperative position to thereby permit locking movement of the lock. 105

4. In a lock, the combination of a bolt, key-actuated mechanism for operating the same, a coin chute, a pair of yieldingly mounted members normally projecting into the path of a coin in the chute, a device movable simultaneously with the bolt, arranged to be normally limited in its movement by 110 said members to thereby prevent locking of the lock, and means connected with said device for moving said members into inoperative position through the intermediary of a coin to thereby permit locking movement 115 of the bolt. 120

5. In a lock, the combination of a bolt, key-actuated means for operating said bolt, a coin-chute, an ejector operable in said chute, an abutment carried by said ejector, a member normally disposed across the path of travel of a coin in said chute, said member being normally positioned to prevent locking of the lock by obstructing the movement of said abutment, and a connection be- 125 130

tween said ejector and said key-actuated mechanism whereby said ejector is caused to displace said member through the intermediary of a coin and thereby permit the 5 lock to be locked.

6. In a lock, the combination of a bolt, key-actuated mechanism for operating said bolt, a coin-chute, a pair of pivotally mounted members yieldingly connected together and normally projecting into said chute, a device movable simultaneously with the bolt, arranged to abut against said normally positioned members to thereby prevent locking movement of the bolt, and means 10 for operating upon a coin in said chute, upon initial movement of said key-actuated mechanism to move said members into inoperative position and thereby permit the lock to be locked.

15 7. In a lock, the combination of a bolt, key-actuated mechanism for operating said bolt, a coin-chute, a pair of yieldingly connected pivotally mounted members normally projecting into said chute and a coin ejector 20 provided with an abutment adapted to engage said members whereby the lock is prevented from being moved into locked position in the absence of a coin from said chute, said ejector being adapted to move 25 said members through the intermediary of a coin out of the path of said abutment, thereby permitting the lock to be locked.

8. In a lock, the combination of a bolt, key-actuated mechanism for operating the 30 same, a moving part operable by said mechanism, a coin-chute, a pair of coaxially mounted yieldingly connected members normally positioned in the path of said moving part of the lock to prevent locking movement of said lock, and an ejector connected to said moving part and operable, in said chute by said key-actuated mechanism to swing said members on their pivot through the intermediary of a coin out of the path 45 of said moving part, to thereby permit the lock to be locked.

9. In a lock, the combination of a coin-chute, a pair of yieldingly mounted opposed members extending into said chute, an 50 ejector reciprocable in said chute adapted to separate the opposed portions of said members by forcing a coin therebetween, a locking bolt, and means for simultaneously moving said bolt and said ejector.

55 10. In a lock, the combination of a coin-chute, a pair of pivotally mounted yieldingly connected members disposed longitudinally of said chute on the back side

thereof and having their lower ends extending into said chute at opposite sides 60 thereof, an ejector reciprocable in said chute and having an abutment disposed above the upper ends of said members and provided with an aperture, said members being normally disposed in the path of travel of said 65 abutment to limit the movement thereof, and means for operating said ejector to force a coin in said chute between the lower ends of said members whereby the upper ends thereof are moved into register with 70 said opening to thereby permit a full stroke of the ejector.

11. In a lock, the combination of a casing provided with a coin-receiving opening, an 75 ejector reciprocable back of said opening, and means for causing said ejector to move laterally so as to close said opening when the bolt is in locked position.

12. In a lock, the combination of a casing 80 provided with a coin-receiving opening, a coin-controlled mechanism for preventing locking movement of the bolt except upon the deposit of a coin in said opening, and means for operating said coin-controlled mechanism through the intermediary of a coin upon locking movement of said bolt, said means being adapted to completely cover and close said opening when the lock 85 is in locked position.

13. In a lock, the combination of a casing 90 provided with a coin-receiving opening, a reciprocable coin ejector disposed within said casing, and means for moving said ejector laterally into position to close said opening upon its ejecting stroke. 95

14. In a lock, the combination of a casing provided with a coin-receiving opening and coin-controlled locking mechanism connected to said casing, said locking mechanism including a locking bolt, a member disposed across said opening, and means for moving the member toward the opening to close the same upon locking movement of the bolt and away from said opening to uncover the same upon unlocking movement of 100 said bolt. 105

15. In a lock, the combination of a casing provided with a coin-receiving opening and coin-controlled locking mechanism connected to said casing, said mechanism including a locking bolt, an ejector, means for moving said ejector longitudinally across said opening, and means for moving said ejector laterally toward and from said opening. 110

ROY D. KING.
